CLOTHES DRIER

Lyman T. Derr, Los Angeles, Calif.

Application March 19, 1948, Serial No. 15,910

5 Claims. (Cl. 211—100)

1

My invention relates to clothes dryers and more particularly to clothes dryers adapted to be used in bathrooms, kitchens or the like.

The object of my invention is to provide a clothes dryers of the character indicated above and equipped with a plurality of drying bars adapted to be folded down into out-of-the-way idle position.

Other objects of my invention may appear in the following specification describing my invention with reference to the accompanying drawing illustrating a preferred embodiment of my invention. It is, however, to be understood that my invention is not to be limited or restricted to the exact construction and combination of parts described in the specification and shown in the drawing, but that such changes and modifications may be made which fall within the scope of the claims appended hereto.

In order that my invention may be understood better, I now proceed to describe my invention with reference to the accompanying drawing, in the several figures of which similar parts are indicated by similar reference characters and in which

Figure 1 is an elevational front view of the clothes dryer according to my invention showing the drying bars in folded down or idle position;

Figure 2 is an elevational side view of Figure 1;

Figure 3 is a top plan view showing the drying bars in working position;

Figure 4 is a sectional view taken substantially on line 4—4 in Figure 1;

Figure 5 is an elevational rear view of the mechanism supporting the dryer arms, parts being broken away to show the construction;

Figure 6 is a sectional view taken substantially on line 6—6 in Figure 5; and

Figure 7 is an elevational front detail view of the wall bracket of the clothes dryer according to my invention.

The clothes dryer forming the subject matter of my invention comprises a wall bracket B preferably made as a stamping from sheet metal and having a circumferential flat rim 10 provided with a plurality of holes 11 and a forwardly projecting convex body 12. The rim is adapted to abut flatly onto a wall 13 or the like and to be fastened onto said wall by means of screws 14 or the like extending through the holes 11. The circumferential outline of the wall bracket B is preferably ovate and the curvature of the convex body 12 is substantially similar to one half of an egg. In the largest portion of the body 12, a horizontal slot 15 is provided extending

2

over nearly the entire surface of this body portion, and a rectangular cut-out 16 extends downwardly from the central portion of the slot 15. The portion of the metal forming the lower edge of the cut-out is bent upwardly to form a flat lip 16a. Two coaxial holes 17 are provided in the wall of the forwardly bulging body 12 somewhat below the lower corners of the horizontal slot 15.

10. An inner bracket P comprises a substantially semi-circular upper plate 18, a substantially semi-circular lower plate 19, and a web 20 connecting the upper and the lower plates. A plurality of dryer bars 21 are arranged between the upper and lower plates as follows. All of the dryer bars are preferably made from sheet steel and are formed to have a U-shaped cross section. The web 22 of each bar is rounded and two holes 23 are provided in each web adjacent one of its ends. On the radii of the upper and the lower plate extending at right angles to the web 20, two holes 24 are provided adjacent the forward edges of said plates at the same distance from each other as the distance between the holes 23 in the bar webs 22.
15. 20. One of the dryer bars 21 is secured rigidly between the upper and lower plates by means of rivets 25 or the like extending through the holes 23 and 24. Rearwardly and laterally toward both sides from the rearward holes 24 in the upper and lower plates 18 and 19, a plurality of rivets 26 extend through said plates and each of these rivets extends through the rearward hole 23 is one of the dryer bars 21 so that these bars are pivotally supported between the bracket plates. All dryer bars are arranged so that their webs 22 are located adjacent the upper plate 18. A downwardly extending lug L is formed on the lower plate adjacent each end of the bracket web 20 and consists of a substantially rectangular rear portion 27 and a front portion 28 having a rounded edge extending downwardly beyond the rear lug portion 27. The front lug portion is off-set inwardly relative to the rear lug portion as shown at 29 and extends at a substantially right angle downwardly from the lower bracket plate, while the rear lug portion extends at an obtuse angle outwardly and downwardly from said plate. A hole 30 is arranged in each front lug portion concentrically with the rounded edge of said lug portion. A shaft 31 extends through the holes 17 in the bracket body 12 and the holes 30 in the front lug portions 28 whereby the inner bracket P is pivotally supported in the wall bracket B, so that the dryer bars 21 may ex-
25. 30. 35. 40. 45. 50.

tend downwardly through the rectangular opening 16 in the wall bracket body 12 and rest against the lip 16a when the inner bracket P is in depending position. A helical spring 32 surrounds each portion of the shaft 31 located between the wall of the bracket body and the adjacent forward lug portion 28 and abuts these two elements in order to impede free swinging motion of the inner bracket and of the dryer bars supported thereby when they are arranged in downwardly folded idle position, as described above. When the dryer bars are to be used to support clothes to be dried, they are lifted up by pivoting the inner bracket P upwardly and the pivotally supported drier bars are swung laterally to enter into the transverse slot 15 in the wall bracket B, whereby the dryer bars are secured in horizontal outwardly extending working position. The upper plate 18 of the inner bracket P is provided on its rounded edge with a pair of rectangular cut-outs 33 forming a forwardly extending tongue 34 adapted to enter the rectangular opening 16 in the wall bracket B. In the rounded edge of the lower plate 19 of the inner bracket P, a pair of similar rectangular cut-outs 35 is provided, forming a forwardly projecting tongue 36 also adapted to enter the opening 16 in the wall bracket when the dryer bars are swung upwardly into working position.

In order to cover the opening 16 and the slot 15 in the wall bracket B, a shield S is provided comprising a body portion 37 curved in all directions and shaped to fit into the rectangular opening 16. On the upper end of the shield body portion, a rearwardly curved laterally extending strip 38 is arranged and on each end of this strip a tongue 39 is formed which is bent rearwardly over the adjacent rear lug portion 27, so that the strip 38 is located in the rear of the slot 15 and the body portion 37 enters and covers the rectangular opening 16, when the inner bracket P is arranged in downwardly extending position and the dryer bars are in idle position as shown in Figures 1 and 2. To secure the lower edge of the body portion 37 to the upper bracket plate 18, a slot 49 is provided in the lowermost portion of said plate and a short tongue 41 formed on the lowermost portion of the body portion 37 engages said slot.

The plate or tongue 41 is of a length, however, to permit its outer or free end portion to serve as a stop or cushion having contact with the upper edge of the slot 38 so that the bars 21 will not strike such upper edge and thus eliminating ugly scarring or burring of the bars 21.

In Figure 5 of the drawings, certain of the bars 21 are shown in full lines as partly spread but it is to be particularly noted that when the bars are fully spread, as indicated by broken lines, the bars are substantially equidistantly spaced. The spacing is automatically obtained

as a result of contact of the inner portion of one bar 21 with the inner portion of the adjacent bar and which inner portions are inwardly of the pivot rivets 26.

I claim:

1. A clothes dryer, comprising a wall bracket having an outwardly curved body, a flat rim encircling said body and apertured to receive fastenings for the securement of the bracket to a supporting surface, an inner bracket pivotally mounted centrally on said body, and a plurality of dryer bars supported by said inner bracket, said body having a horizontal slot and a substantially rectangular opening extending downwardly from the central portion of the slot, the centrally located of said dryer bars being rigidly secured to said inner bracket and the other of the dryer bars pivotally mounted thereon and adapted to be swung laterally into engagement with said slot, when the inner bracket is swung into horizontal position.

2. The invention as defined in claim 1, with a shaft extending horizontally through said body and pivotally supporting said inner bracket, a downwardly extending lug on each lateral end of said inner bracket, said shaft passing through said lugs, and a spring on each end of said shaft and frictionally bearing against an adjacent lug and the wall of said body.

3. The invention as defined in claim 1, wherein all of said other dryer bars are adapted to be disposed in close parallel relation with respect to each other and to said centrally located dryer bar with their upper ends disposed in said opening, when said inner bracket and the dryer bars are pivoted downwardly to vertical position.

4. The invention as defined in claim 1, with a plate, constituting a shield, secured to said inner bracket and adapted to cover the slot and opening in said body, when said inner bracket and said dryer bars are disposed in vertical position.

5. The invention as defined in claim 1, with said inner bracket comprised in an upper plate, a lower plate, and a web connecting said plates, and said dryer bars are of inverted U-shape in cross-section and disposed between said plates.

LYMAN T. DERR.
